UNITED STATES PATENT OFFICE.

WILLIAM O. ALDRICH, OF WHITINSVILLE, MASSACHUSETTS, ASSIGNOR TO THE WHITIN MACHINE WORKS, INCORPORATED, OF WHITINSVILLE, MASSACHUSETTS.

THREAD-GUIDE SUPPORT.

SPECIFICATION forming part of Letters Patent No. 761,934, dated June 7, 1904.

Application filed March 9, 1904. Serial No. 197,340. (No model.)

To all whom it may concern:

Be it known that I, WILLIAM O. ALDRICH, a citizen of the United States, residing at Whitinsville, in the county of Worcester and State 5 of Massachusetts, have invented a new and useful Improvement in Thread-Guide Supports for Spinning or Twisting Machines, of which the following is a specification.

This invention has reference to an improvement in the construction of sheet-metal thread-guide supports for spinning or twisting machines.

In spinning or twisting machines the thread-guide supports usually consist of finger-boards carrying guide-eyes and finger-board heads hinged to the side bars of the machine and pivotally supporting the finger-boards.

The object of my invention is to improve the construction of sheet-metal finger-boards 20 and finger-board heads and by this improved construction to hold the finger-boards in their normal or turned-down position more firmly than has heretofore been done.

A further object of my invention is to hold 25 the guide-eyes as rigidly as possible, and I accomplish this object by forming the stop or support for the finger-board centrally on a line with the guide-eye and strengthen the support by stamping up ribs on the support 30 and finger-board parallel with the guide-eye stem.

My invention consists in the peculiar and novel construction of the finger-board and the finger-board head, as will be more fully 35 set forth hereinafter.

Figure 1 is a top plan view of my improved thread-guide support detached from the side bar of the machine, showing all but two of the finger-boards and adjacent finger-board 40 head broken away to clearly show my invention. Fig. 2 is a plan view looking at the under side of one of the finger-boards and adjacent portion of the finger-board head.

Fig. 3 is a vertical sectional view taken on line X X of Fig. 1, showing the finger-board 45 in the turned-down position and the means of securing the finger-board head to the side bar of the machine. Fig. 4 is a vertical detail

view looking at the back of the finger-board head, showing the leaf of the hinge raised to 50 clearly show the construction of the hinge. Fig. 5 is a detail sectional view taken on line Y Y of Fig. 4, showing the parts of the hinges formed integral with the finger-board and finger-board head; and Fig. 6 is an enlarged 55 vertical sectional view similar to Fig. 3, showing the finger-board in the turned-up position for doffing the bobbin.

In the drawings, *a* indicates the side bar of a spinning-frame; *b*, the finger-board head; *c c*, the finger-boards, and *d d* the guide-eyes. The finger-board head *b* is stamped or pressed from sheet metal to form integral the flat top *b'*, the back *b''*, the closed ends *b''' b'''*, in which are the holes *b⁴ b⁴*, and the hinge-knuckles *b⁵ b⁵* and *b⁶ b⁶*. The knuckles *b⁵ b⁵* on the front are formed by rolling outwardly-extending tongues over to form a cylindrical knuckle, and the knuckles *b⁶ b⁶* are formed by cutting the tongues from the back *b''*, bending 70 them upward, and forming them into the cylindrical knuckles, as shown in Figs. 4 and 5. These knuckles *b⁶ b⁶* coöperate with a pintle and the knuckle *b⁷* on the butt *b⁸* to form a hinge, which is secured to the side bar *a* of 75 the machine by screws in the usual way.

The finger-board head *b* is preferably made in sections supporting ten or twelve finger-boards and may be secured together by bolts through the holes *b⁴ b⁴* in the ends *b''' b'''*; but, 80 if desired, they could be made in one continuous piece extending the entire length of the machine.

The finger-boards *c c* are stamped from sheet metal to form integral the flat body portion *c'*, the downwardly-extending lip *c''* on the front, in which is the notch *c³* for the guide-eyestem, the hinge-knuckles *c⁴ c⁴*, formed from tongues on the body portion *c'*, and the hook-shaped inwardly-extending arm *c⁵*, with 85 the stamped-up strengthening-ribs *c⁶ c⁶*, adapted to extend centrally under and bear on the under side of the finger-board head *b* to form a stop and hold the finger-board in its normal or turned-down position, as shown in Fig. 3. 95 The knuckles *c⁴ c⁴* coöperate with the wire

pintle c^7 and the knuckle b^5 to form a hinge pivotally connecting the finger-board with the finger-board head. The strengthening-ribs c^6 c^8 extend forward on the under side of the finger-board and stiffen the same. The wire guide-eye d has the shank d' , on the outer end of which is the usual coil, forming the eye d'' . The inner end d'' is bent approximately **T**-shaped to prevent the shank turning under the clamp d^4 , secured to the under side of the finger-board by the bolt d^5 , as shown in Fig. 2.

In the use of my improved sheet-metal thread-guide supports the finger-boards are supported and stiffened centrally and the guide-eyes more firmly held in their operative positions by this central supporting and stiffening of the finger-boards than has heretofore been done.

Having thus described my invention, I claim as new and desire to secure by Letters Patent—

1. In a thread-guide support for spinning or twisting machines, a sheet-metal finger-board head having flanges forming a back and ends, parts formed integral with the finger-board head coöperating with pintles and butts to form hinges on the back of the finger-board head, sheet-metal finger-boards, parts formed integral with the finger-boards and finger-board heads coöperating with pintles to form

hinges connecting the finger-boards with the finger-board heads, means for supporting the finger-boards in their turned-down position consisting of a central arm on the finger-boards adapted to extend under and bear on the under side of the finger-board head, means for stiffening the central arm and finger-boards consisting of ribs on the arm and finger-board extending centrally toward the front of the finger-board, and means for adjustably securing guide-eyes to the finger-boards, as described. 35 40

2. In a thread-guide support for spinning or twisting machines, a sheet-metal finger-board having a flat body portion, parts forming the knuckles of a hinge, a central arm adapted to support the finger-board in its turned-down position, and means for stiffening the arm and body portion centrally consisting of ribs on the arm and body portion all formed integral, and means for adjustably securing a guide-eye to the finger-board, as described. 45 50

In testimony whereof I have signed my name to this specification in the presence of two subscribing witnesses.

WILLIAM O. ALDRICH.
